(57) **CLAIM**

The ornamental design for a bicycle with panniers, as shown and described.

DESCRIPTION

FIG. 1 is a top, rear, and left side perspective view of a bicycle with panniers showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a top, rear, and left side perspective view thereof, in which the panniers are in a collapsed configuration.

The broken lines in the drawings illustrate portions of the bicycle with panniers that form no part of the claimed design.
